PRICE TAG

William A. Godsoe, Burbank, Calif., assignor to
 A. Kimball Company, New York, N. Y., a corporation of New York

Application February 2, 1938, Serial No. 188,265

3 Claims. (Cl. 40—25)

This invention relates to price tags.

It is an object of the invention to provide a price tag adapted to be secured to an article of merchandise by means of the usual metal pin or staple, and in which the said pin or staple is covered by the material of the tag in such manner as to prevent injury to salesmen and customers handling the merchandise.

It is a further object of the invention to provide a price tag, which, when secured to the merchandise, provides an extended body portion projecting therefrom on which price information may be printed. Parts of said body portion may be trimmed or severed therefrom without removing the tag from the goods.

Other objects and advantages of the invention will appear hereinafter.

A preferred embodiment of the invention selected for purposes of illustration is shown in the accompanying drawing, in which,

Figure 1 is a plan view of the tag.

Figure 2 is a longitudinal section on the line 2—2 of Figure 1.

Figure 3 is a plan view showing the first step in attaching the tag to the merchandise.

Figure 4 is a similar view showing the next step in attaching the tag.

Figure 5 is a section on the line 5—5 of Figure 4.

Figure 6 is a plan view showing the tag as finally attached to the merchandise.

Figure 7 is a section on the line 7—7 of Figure 6.

Referring to the drawing, the tag comprises a body portion 1 of any convenient size and area desired to accommodate the price and other information to be printed thereon. At one end of the body portion 1, the material of which the tag is made is folded along fold line 2 to provide a flap 3, and is then reversely folded along fold line 4 to provide end flap 5.

End flap 5 has secured to the leading edge thereof an attaching staple 6 of any desired construction, and having prongs or pins 7 adapted to penetrate the goods in the usual manner. Flap 3 is provided with an aperture 8 adapted to register with the pins 7, so that after the pins have been passed through the goods as illustrated in Figure 3, the tag may be folded along fold line 4, the pins pass through the aperture 8 and may be spread or clinched as shown in Figure 4 to secure the tag to the goods.

A locking tab 9 is formed in the flap 3, preferably by means of a crescent shaped slit 10 terminating in apertures 11. A slot 12 is also formed in the body portion 1 in such position that when the tag is folded along fold line 2, as illustrated in Figure 6, the tab 9 may be pushed through the slot 12. The slot 12 is preferably slightly shorter

than the width of the tab 9, so that when the tab is pushed through the slot, the ears 13 lock the tab in place and prevent its accidental withdrawal. Thus, while this tag is not intended to serve fully the purposes of the so-called "security" tags, which are intended to prevent unauthorized removal, it does serve those purposes to some extent, for once the tab 9 is pushed through the slot 12, it is difficult to withdraw it without tearing the ears 13.

It will be understood that the invention may be variously modified and embodied within the scope of the subjoined claims.

I claim as my invention:

1. A price tag comprising, a body portion, a pair of connected flaps at one end thereof including an end flap and an intermediate flap, a staple secured to the end flap, said intermediate flap having an aperture registering with the pins of said staple, a tab formed in said intermediate flap, and said body portion being of a length greater than the length of either of said flaps and being provided with a slot to receive said tab, said tab being formed by a slit terminating in apertures indenting said tab and forming ears on said tab adapted to lock against the ends of said slot.

2. A price tag comprising, a body portion, a pair of connected flaps at one end thereof including an end flap and an intermediate flap, reversely directed lines of fold between said body portion and said intermediate flap and between said intermediate flap and said end flap, a staple secured to the end flap, said intermediate flap having an aperture registering with the pins of said staple, a tab formed in said intermediate flap, the base of said tab coinciding with the line of fold between said end and intermediate flaps, and said body portion being of a length greater than the length of either of said flaps and being provided with a slot to receive said tab.

3. A price tag comprising a body portion, a pair of connected flaps at one end thereof including an end flap and an intermediate flap, reversely directed lines of fold between said body portion and said intermediate flap and between said intermediate flap and said end flap, a staple secured to the end flap, said intermediate flap having an aperture registering with the pins of said staple, a tab formed in said intermediate flap, the base of said tab coinciding with the line of fold between said end and intermediate flaps, and said body portion being of a length greater than the length of either of said flaps and being provided with a slot to receive said tab, said tab being formed by a slit terminating in apertures indenting said tab and forming ears on said tab adapted to lock against the ends of said slot.
